MACHINE FOR CASTELLATING NUTS.

1,157,258.

Specification of Letters Patent. Patented Oct. 19, 1915.

Application filed July 21, 1914. Serial No. 852,168.

To all whom it may concern:

Be it known that we, OSCAR A. SMITH and BENJAMIN F. RINDFLEISCH, citizens of the United States, residing at Cleveland, in the 5 county of Cuyahoga and State of Ohio, have invented certain new and useful Improvements in Machines for Castellating Nuts, of which the following is a specification.

This invention relates to means or punch 10 presses for castellating nuts, the object of the invention being to provide improved means which will successfully castellate nuts and stand up during the carrying on of this work, and which will permit the use of a 15 strong and lasting punch and die.

Ordinarily the punches used for castellating nuts are very light, usually being the 20 width of the slot, and in consequence it is impracticable to punch the nuts from the outside toward the center because, owing to the comparative narrowness of the punch and the lightness of its construction, which is necessary in order that the punch pass into the slot, the punch quickly collapses and 25 wears out, and so far as we are aware no practical means have been devised by means of which a heavier punch may be used. Moreover, another serious fault is that the 30 die must be only large enough in diameter to accommodate the nut and yet contain the necessary number of slots, and therefore it collapses very readily. If only one slot is put in the die the wear is six times as great, and the nut must be revolved inside the die, 35 while in the present improvement it is revolved with the die.

One of the objects of the invention is the provision of a mechanism of the character described by means of which the power will 40 be delivered close to the cutting point of the punch.

Another object of the invention is the provision of means for locking the punch against endwise and sidewise play.

Another object of the invention is the provision of means for protecting the punch from the slugs punched from the nut.

Another object of the invention is the provision of a strong and efficient punch.

Another object of the invention is the provision of means for indexing and accurately locking the die after it is indexed and for insuring the proper position of the nut during the punching operation.

Another object of the invention is the provision of means for feeding the nut into position and holding it in position while in the die.

Another object of the invention is the provision of means for holding the nut in 60 proper relation to the slots in the die after it is punched and during successive punching operations.

Another object of the invention is the provision of means for discharging the punched 65 nut after the punching operations are completed.

Another object of the invention is the provision of an improved die whereby the same 70 will automatically clear itself.

Another object of the invention is the provision of an improved nut castellating machine having the several novel features hereinbefore referred to and so organized and combined that a very short downward stroke 75 of the ram, not ordinarily exceeding two inches, will be sufficient to punch and clear the punch, rotate the nut blank and lock it accurately in position for the repeated strokes necessary for the punching of the 80 nut, and in which machine the length of the punch arm is such that not only may the reinforced punch construction shown be used and the power of the blow delivered directly in line with the point and close to it, thereby 85 preventing any tendency to spring or to make the stroke uncertain and less effective owing to any lost motion or spring of the tool, but an almost flat bottom slot, that is one in which the bottom is practically parallel 90 with the bottom of the nut, is obtained.

As a result of practical tests of this improved mechanism the method of punching nuts has been practically revolutionized, as 95 well as the cost of so doing very materially lessened, the mechanism having shown itself to be thoroughly practical from a mechanical standpoint and extremely economical in practice, it being capable of being operated by unskilled help and yet its production is 100 remarkable compared with nut castellating machines heretofore used, and especially is this so when it is considered that with a stroke not usually exceeding two inches there is sufficient force to do the necessary punching and sufficient time within which to properly index and lock the die in position for the successive punching operations.

In the drawings accompanying and forming part of this specification, Figure 1 is a front perspective view of this improved machine; Fig. 2 is a right hand side perspective view of the machine shown in Fig. 1; Fig. 3 is an enlarged detail front view of a part of the machine shown in Fig. 1; Fig. 4 is a cross-sectional view taken in line 4—4; Fig. 5 is a detail top view of the lower half of the machine shown in Fig. 4; Fig. 6 is a detail perspective view of the magazine and the semi-automatic means for feeding the nut blanks; Fig. 7 is a detail sectional view of Fig. 6; Fig. 8 is a detail enlarged view of Fig. 7 and a sectional view of the die and the means for holding it in position; Fig. 9 is a detail view of the blank releasing means; Fig. 10 is a detail end view of the feed plunger; Fig. 11 is a perspective view of the punch and its holder, illustrating the means for conveying the power directly adjacent to the point of the punch; Fig. 12 is a detail view of the locking means carried by the ram for positioning the die; Fig. 13 illustrates a view of the improved reinforced punch; Fig. 14 illustrates the means for preventing endwise play of the punch; Fig. 15 illustrates the various members of the die and its carrier; Fig. 16 is an enlarged sectional view of a part of the ring shown at the left of Fig. 15; Fig. 17 is a view of the die and one of its locking means; Fig. 18 is a sectional view illustrating the respective positions of the die, the punch and the feed plunger; Fig. 19 is a view of a castellated nut; Fig. 20 is a perspective view illustrating the means for indexing and locking the nut blank carrier or die; Fig. 21 is a partly sectional view illustrating a part of the indexing means shown in Fig. 20; and Fig. 22 is a perspective view also illustrating part of the indexing means shown in Fig. 20.

Similar characters of reference indicate corresponding parts in the different figures of the drawings.

The present improved mechanism has to do mainly with the punching of blanks such as nut blanks having a cylindrical hole axially of the blank, and in the present instance the several elements making up the machine are applied to a punch press of any suitable style, and a detailed description of which is unnecessary except in so far as it has to do with the numerous improved features thereof, and therefore a brief description of such a press only is deemed necessary in the present instance.

The punch press shown comprises the usual standard or base 2 having the usual power driven wheel 3, the shaft 4 and ram 5, the treadle 6 and connecting means therebetween and the usual clutch carried by the shaft. Suitably mounted upon the punch press is the punch 10, which is provided

with a narrow rib-like point 11 the width of the slot to be punched, and as this point must be narrow to correspond with the size of slot desired it follows that unless such punch is materially reinforced it is very weak and inefficient. It is understood, of course, that different sizes of slots require different sizes of punches. This punch is formed in such a manner that it widens out considerably just back of the point, thereby making a very much stronger punch than the ordinary punch, which is, as stated, usually of the same thickness as at the point, and in the present instance the punch is shown with a rounded tapered surface tapering from the thickened body 12 toward the point. By means of this construction a very heavy, rigid and reinforced punch is obtained. This punch is carried by a punch holder in the form of an arm 13 pivoted on a shaft 14, (see Fig. 11), which shaft 14 is supported on a bearing block 14' and the shaft is held in position by bearing caps 14'' capable of sliding on bolts by means of elongated slots so that the bearing caps may be slid apart to permit the pivot or shaft 14 and the punch arm to be removed and replaced. A lock block 15 holds the punch in position sidewise, while a cylindrical lock block 16 and an adjusting screw 17 hold it in position endwise. By means of this cylindrical lock block 16 and adjusting screw 17, the lock block fitting into grooves 18 of the holder, it is found practical to prevent the punch from working out of its arm 13 or holder endwise, as the bearing of the cylindrical lock block 16 in its cylindrical grooves makes the lock positive while the adjusting screw permits of any desired relation between the punch and this cylindrical block. Ordinarily in the operation of this press the ram thereof would strike on the top of the punch arm at the point *a*, which would be a considerable distance removed from the working point of the punch, and it was found that the continual action of the power at a point so far back of the actual cutting point had a tendency to bend the point of the punch upward and destroy its usefulness. In the present improvement, therefore, this disadvantage has been entirely eliminated by the provision of means which enables the power to be applied at approximately the cutting point of the punch, in that while the stroke of the ram is still delivered at the point *a* it is delivered in such a manner that it is transmitted adjacent to the cutting point of the punch, and for this purpose a hardened cylindrical ram extension 19 is provided, this extension being set into the punch holder or arm on an angle so that while the top of this extension is some distance back from the point of the punch yet the power will be applied to the punch within a short distance from its

point. This ram extension 19 extends somewhat above the punch carrying arm, so that the ram will always strike on the end of the extension instead of striking on the top of the punch arm. This ram extension 19 is a loose fit in the arm and transmits the power directly from the ram to a point adjacent to the cutting point of the punch, and consequently prevents any bending of the punch during its operation. Moreover, owing to the manner of supporting the punch, which makes possible the distance between the point of the punch and its pivotal support 14' the punch, in traveling from the bore of the nut outwardly, travels practically in almost a straight line. In other words, while the horizontally located punch moves in an arc of a circle, yet its movement is such that in this distance the arc is almost a straight line, thus resulting in the production of an almost flat bottomed slot.

We provide an improved die 20 to cooperate with the punch, (see Figs. 15 and 17), and this die is provided with as many slots 21 as it is desired to punch in the nut or other piece to be slotted, these slots communicating with an axial opening or bore 22 in the die which receives the nut blank in the manner hereinafter described. These radial slots are formed in an annular projection or what may be called a hub 23 of the die, and at their outer ends the slots communicate with an annular recess or clearance way 24, so that the slugs punched out of the nut or other piece being operated upon—the punch working, it will be understood, from the center of the hole in the nut outwardly and through a slot in the die,—will drop clear of both the punch and the die by reason of this clearance way. To insure that the slugs are not retained inside the groove or clearance way of the die and so be carried up and drop into the inside of the die and interfere with the punch during the indexing of the die, a guard 25, (see Figs. 15 and 18), of any suitable form may be used. In the present instance this guard fits loosely over the punch, (see Fig. 18), and in front of the surface 26 of the die. This guard plate is provided with an opening in the form of a key-hole slot 27 for the reception of the end of the punch, and this guard is so located that there is just sufficient room for clearance between the face of the punch arm and the guard and between the guard and the face of the die. The die is also provided with a peripheral annular projection or rim 28, and this die sets into a ring 29, which is provided with as many indexing and locking recesses or grooves 30 as there are slots in the die. In other words, the number of grooves or recesses in the ring corresponds with the number of slots in the die, and of course these slots correspond in number with the num-

ber of slots that the nut is to have. The die and the ring, which will hereinafter be called the index ring, since it is by this means in part that the die is indexed, are maintained in proper relation by means of a locating pin 31 fitting into registering grooves 31' and 31'' of the ring and die respectively, (see Fig. 18), and a holder plate 32 which is bolted to the ring 29.

As the nut blanks are fed into position for slotting in the manner hereinafter described, they pass through the axial opening in the holder plate 32. This holder plate is provided with a pair of spring tensioned jaws 33 dovetailed into the holder plate, and tension on these jaws is obtained by expansion springs 36, (see Figs. 15 and 16). This holder plate is fastened to the front face of the index ring 29 and revolves with it. The index ring is carried by a steel bearing ring 37 supported by a bracket 38, and this latter ring is effective to take up any wear that may occur between the index ring 29 and the holder plate 32. The holder plate 32 is adjustable so that the nuts or other blanks being fed through the jaws thereof will come in exact alinement with the punch and die when the die is locked in position, and this adjustability is obtained by means of elongated slots 34 in the holder plate 32. These slots are for the reception of screws 35 which pass into the index ring 29. As the nuts or other pieces are forced between the jaws 33, these jaws may expand slightly to permit of the passage of a corner of the nut should it not be fed exactly straight with the face of the jaw, but the springs are strong enough to straighten the piece and to make a flat bearing between the face of the jaw and the side of the blank or nut.

Carried by the ram 40 is a hardened locking dog 41 having a tooth-shaped point 42. This dog is pinned to the ram by a pin 43, and the pin is made small enough to permit of shearing it in case the mechanism for indexing should become jammed or otherwise inoperative and the dog should hit on the cylindrical surface of the index ring rather than into one of the index recesses or grooves in the periphery thereof. In the operation of the ram this locking dog comes into engagement with that particular groove or recess in the index ring 29 which is at the time at the top central position of the index ring and so properly aligns and locks the index ring during the ram stroke on the punch. In addition to this locking means, means for positioning the die is also provided, this consisting of an auxiliary index positioning device or locking bolt 44. This bolt is pivoted on a screw pin 45 carried by a U-shaped bracket, (see Figs. 17, 18 and 20), and is swung into engagement to enter one of the slots or recesses in the index ring each time

the ring is indexed, the bolt engaging that particular recess or slot which has just been previously engaged by the locking device just described carried by the ram. This bolt is of course withdrawn from the slot to permit the indexing of the index ring and die, and this is accomplished by means of a cam 46 carried by a special cam disk 47 located on the fly wheel shaft of the ram, and this cam disk cooperates with a lever 48 pivoted to the framework of the press, and the lower end of which engages this lock bolt so as to swing it free of the slot or recess in the index ring, the lower end of the lever and outer end of the lock bolt having attached thereto a plurality of springs 48' which act through the medium of the lever to force the bolt successively into the slots or recesses of the index ring. Several of these springs are provided so that should one of them break there will be no failure of the bolt to lock the index ring. By this mechanism it will be seen that the cam operating on the lever just described will swing the bolt from its slot or recess in the index ring to permit the indexing thereof, and that as soon as the index ring has been rotated or indexed, and therewith the die, the springs just described will return or drop the bolt into engagement with the next recess or groove of the index ring and so hold it in position, and that when the ram descends to operate the punch it will be aligned and locked by the locking tooth shown in Fig. 12 and carried by the ram as hereinbefore described.

For indexing the index ring and thereby the die, suitable means is provided, and this consists in the present instance of an indexing lever 50 so pivoted on a pin 51 carried by the framework of the press that the indexing lever not only has a swinging movement in a vertical plane, but also has a slight movement in a horizontal plane, this result being obtained by forming the pivot hole to permit this. See Fig. 5. This indexing lever 50 is provided at its end with a pin 52 in position to project into one of the slots or recesses of the index ring. This indexing lever 50 is actuated by an auxiliary member or lever 53, the upper end of which is secured to a cross slide 54 of the ram, (see Figs. 3 and 20), and this auxiliary lever 53 is provided with a cam projection or face 55 engaging the under edge of the indexing lever 50, a stud 56 being located in position to return the lever 50 to proper index position. Each time the ram moves upward the lever 53 is likewise carried upward and during this upward movement the indexing lever 50 is likewise moved upward in a vertical plane, and owing to the fact that the indexing pin 52 has previously dropped into a slot or recess of the index ring the index ring is revolved, in the present instance owing to the fact that six slots

are shown, one-sixth of a revolution so as to index the ring and thereby the die, and of course the nut blank carried thereby, which revolves with the die.

When the index ring has been revolved the predetermined distance, the auxiliary indexing bolt hereinbefore described will be dropped into position to properly space the index ring and prevent any extensive movement thereof in either direction. During the indexing and until the completion thereof the straight side of the index pin 52 is maintained firmly in contact with the straight side wall of the slot or recess into which the pin projects, and this is accomplished by so forming the cam surface at the lower end of the lever 53, as by undercutting it, and by beveling the lower edge of the lever 50, that the cam surface will have a tendency to hold the lever 50 firmly against the side of the lever 53 while allowing the lever 50 to move across the lever 53 during its upward travel, a spring plunger 58, (see Figs. 5 and 20), being provided to assist in this result. This spring plunger 58 forces the index lever 50 against the index ring 29, see Fig. 5. This is necessary for the reason that the index pin 52 on the lever 50 will instantly drop into one of the stations 30 at the proper time and then when the lever 53 comes in contact with the index lever 50, the cammed sections 55 on levers 50 and 53 prevent pin 52 from slipping out of contact with the index stations on cam ring 29, but before this camming action takes place the spring plunger 58 is the medium that presses the index pin 52 on lever 50 in connection with the index stations of index ring 29. This action of the lever 50 is shown plainly in dotted lines in Fig. 5. The upward movement of the lever 50 is limited by a projection or pin 59, (see Fig. 20). On the downward stroke of the ram slide the indexing lever 50 is carried downward, camming the index pin 52 thereof out of its slot or recess of the index ring by reason of the taper on the back of this pin 52 and the cut away formation of the index ring, the pressure of the spring plunger 58 being thus overcome at this time, so that the pin 52 will be withdrawn from its slot or recess and be carried along the face of the index ring during the remainder of the downward travel of the lever 50 and until it drops into the next slot or recess of the index ring ready for the next indexing movement, and a stop 59' is located in position at the underside of the lever 50, and this stop together with stop 59 hereinbefore described form safety stops to prevent the overrunning of the stroke.

For the purpose of returning the punch to its original position ready for the next slot, a spring plunger 60 is provided, (see Figs. 3 and 4). This plunger is supported below the punch carrying arm or holder, and the

plunger has a constant bearing upon the underside of this arm during its idle and cutting movements. As the ram descends this plunger is forced downward and the spring 61 thereof is compressed, and as the ram moves upward this spring expands and through the medium of the plunger, lifts the punch carrying arm and in this way shifts the punch from the slot which it has cut and out of the slot of the die and carries the punch into position for the next stroke of the ram. The position to which the punch is shifted is controlled by adjusting nuts 62 and 63 at the bottom of the rod forming the plunger.

In the present improvement the nut blanks are semi-automatically fed to the die and punch, and for this purpose a magazine 70 is provided, which is bolted to a bracket 71 located in front of the die. It will, of course, be understood that the magazine is changed for different sizes of nut blanks. The nut blanks are held in the magazine by a plate 72 and drop freely into position before a feed rod 73, which is controlled by a hand lever 74 pivoted at the front of the machine to a bracket 75 extending therefrom. This feed rod is held in a bushing or guide block 76 located in an angular extension of the magazine, (see Fig. 6). The size of the end of the feed rod is, of course, varied to fit the different sizes of holes, and the point is just long enough so that when forced fully into the nut it will clear the punch. As the feed rod is pushed forward by its handle the free end thereof, which is slotted to give it a slight spring tension, enters slightly into the hole in the lower blank, and as the blank is pushed forward by the continued forward movement of the feed rod this blank comes in contact with the rounded corner 77 of a spring pressed plunger 78, (see Figs. 7, 8 and 9), located in the rear wall of the magazine. This contact of the blank with the plunger retards the blank sufficiently to permit the slotted end of the feed rod to fully enter the hole of the blank and until the shoulder 79 at the end of the feed rod, (see Fig. 7), comes against the face of the blank. The slotted end of the feed rod is not supposed to be a tight fit in the blank, but is intended to fit sufficiently snug to carry the blank out of contact with the plunger 78 and force it upward to compress its spring 80 when the blank is fully seated against the shoulder 79 of the feed rod, and when this has occurred the blank will be forced across the opening between the face of the magazine and the spring jaws of the holder plate 32 hereinbefore described. As the blank is forced through the jaws these jaws contract on it and in some cases shift its position somewhat around the end of the feed rod, so that the square faces of the jaws hit the square sides of the blank in the manner

hereinbefore described. As these jaws of this holder plate 32, the die and the index ring revolve, the blank, which is only a snug fit on the end of the feed rod, also revolves on this rod.

After the blank has been punched in the manner hereinbefore described the feed rod is withdrawn by the handle, the tension of the slotted end of the feed rod in the blank being sufficient to withdraw the blank from between the spring pressed jaws of the holder plate 32. As the feed rod is still further withdrawn the back of the castellated blank, which extends slightly above the top of the feed rod, comes into contact with the opposite sharp corner of the plunger 78, and in this manner the end of the feed rod is withdrawn from the blank and the castellated blank drops out of the way of the blank following it.

From the foregoing it will be observed that by reason of the fact that the punch and the die are not connected in any way with the ram or the ram slide, or with the power driven shaft, any lost motion of the ram or the ram slide or the shaft, or at the pivotal point of the punch, does not affect the action of the punch, and especially is this so because the application of the power of the ram on the punch is so much closer to the punching end of the punch than to the pivotal point of such punch. Moreover, it will also be observed that owing to the organization of this machine a two-inch or less stroke of the ram is sufficient to effectively do the work of punching and indexing a blank successively, to castellate it. In other words, all movements are very short, and consequently can be made very rapidly, which shows a decided economy in time and production.

We claim as our invention:

1. In a machine of the class described, the combination of a reciprocating ram, a nut-blank die, means located at one side of said die for supporting it, a punch formed to castellate nut blanks and extending transversely to the direction of reciprocation of the ram, said die constructed to receive the punch at its opposite side, and means for delivering the power of the ram to the punch adjacent to the cutting part thereof from a point in the rear of such part.

2. In a machine of the class described, the combination of a reciprocating ram, a nut blank die, a nut castellating punch extending transversely to the direction of reciprocation of the ram, and means for delivering the power of the ram to the punch adjacent to the cutting part thereof from a point in the rear of such cutting part, said means comprising an inclinedly located lengthwise sliding member with one end in position to be engaged by the ram and the other end in engagement with the punch.

3. In a machine of the class described, the combination of a reciprocating ram, a nut-blank die, means located at one side of said die for supporting it, a punch formed to castellate nut blanks and free of connection with said ram, said die constructed to receive the punch at its opposite side, and means for delivering the power of the ram to the punch adjacent to the cutting part thereof from a point in the rear of such cutting part and forward of the rear end of such punch.

4. In a machine of the class described, the combination of a reciprocating ram, a die, a punch free of connection with said ram, and means for delivering the power of the ram to the punch adjacent to the cutting part thereof from a point in the rear of such cutting part, said means comprising an inclined member having one end in position to be engaged by the ram and the other end in position to engage the punch.

5. In a machine of the class described, the combination of a reciprocating ram, a die, a punch extending transversely to the direction of reciprocation of the ram, means for delivering the power of the ram to the punch adjacent to the cutting part thereof from a point in the rear of such cutting part, and means for indexing the die and the blank carried thereby.

6. In a machine of the class described, the combination of a reciprocating ram, a die, a punch free of connection with said ram, means for delivering the power of the ram to the punch adjacent to the cutting part thereof from a point in the rear of such cutting part and forward of the rear end of such punch, and means for indexing the die and the blank carried thereby.

7. In a machine of the class described, the combination of a reciprocating ram, a die, a punch extending transversely to the direction of reciprocation of the ram, means for delivering the power of the ram to the punch adjacent to the cutting part thereof from a point in the rear of such cutting part, and means operated by the ram for indexing the die and the blank carried thereby.

8. In a machine of the class described, the combination of a reciprocating ram, a die, a punch free of connection with said ram, means for delivering the power of the ram to the punch adjacent to the cutting part thereof from a point in the rear of such cutting part, and means operated by the ram for indexing the die and the blank carried thereby.

60 9. In a machine of the class described, the combination of a reciprocating ram, a die, a punch extending transversely to the direction of reciprocation of the ram, means for delivering the power of the ram to the punch adjacent to the cutting part thereof

from a point in the rear of such cutting part, means for indexing the die and the blank carried thereby, and means for locking the die after each indexing thereof.

10. In a machine of the class described, the combination of a reciprocating ram, a die, a punch free of connection with said ram, means for delivering the power of the ram to the punch adjacent to the cutting part thereof from a point in the rear of such cutting part, means for indexing the die and the blank carried thereby, and means for locking the die after each indexing thereof.

11. In a machine of the class described, the combination of a reciprocating ram, a die, a punch extending transversely to the direction of reciprocation of the ram, means for delivering the power of the ram to the punch adjacent to the cutting part thereof from a point in the rear of such cutting part, means for indexing the die and the blank carried thereby, and means carried by the ram for locking the die after each indexing thereof.

12. In a machine of the class described, the combination of a reciprocating ram, a die, a punch free of connection with said ram, means for delivering the power of the ram to the punch adjacent to the cutting part thereof from a point in the rear of such cutting part, means for indexing the die and the blank carried thereby, and means carried by the ram for locking the die after each indexing thereof.

13. In a machine of the class described, the combination of a reciprocating ram, a die, a punch extending transversely to the direction of reciprocation of the ram, means for delivering the power of the ram to the punch adjacent to the cutting part thereof from a point in the rear of such cutting part, means for indexing the die and the blank carried thereby, automatically operative means for positioning the die after each indexing thereof, and locking means carried by the ram for locking the die against movement.

14. In a machine of the class described, the combination of a reciprocating ram, a die, a punch free of connection with said ram, means for delivering the power of the ram to the punch adjacent to the cutting part thereof from a point in the rear of such cutting part, means for indexing the die and the blank carried thereby, automatically operative means for positioning the die after each indexing thereof, and locking means carried by the ram for locking the die against movement.

15. In a machine of the class described, the combination of a reciprocating ram, a die, a punch extending transversely to the direction of reciprocation of the ram, means for delivering the power of the ram to the

- punch adjacent to the cutting part thereof from a point in the rear of such cutting part, means for indexing the die and the blank carried thereby, means automatically operative to lock the die after each indexing thereof, and means for feeding blanks successively to the die.
16. In a machine of the class described, the combination of a reciprocating ram, a die, a punch free of connection with said ram, means for delivering the power of the ram to the punch adjacent to the cutting part thereof from a point in the rear of such cutting part, means for indexing the die and the blank carried thereby, means automatically operative to lock the die after each indexing thereof, and means for feeding blanks successively to the die.
17. In a machine of the class described, the combination of a reciprocating ram, a die, a punch extending transversely to the direction of reciprocation of the ram, means for delivering the power of the ram to the punch adjacent to the cutting part thereof from a point in the rear of such cutting part, means for indexing the die and the blank carried thereby, automatically operative means for positioning the die after each indexing thereof, locking means carried by the ram for locking the die, and means for feeding blanks successively to the die.
18. In a machine of the class described, the combination of a reciprocating ram, a die, a punch free of connection with said ram, means for delivering the power of the ram to the punch adjacent to the cutting part thereof from a point in the rear of such cutting part, means for indexing the die and the blank carried thereby, automatically operative means for positioning the die after each indexing thereof, means carried by the ram for locking the die, and means for feeding blanks successively to the die.
19. In a machine of the class described, the combination of a reciprocating ram, a die, a punch extending transversely to the direction of reciprocation of the ram, means for delivering the power of the ram to the punch adjacent to the cutting part thereof from a point in the rear of such cutting part, means for indexing the die and the blank carried thereby, automatically operative means for positioning the die after each indexing thereof, means carried by the ram for locking the die, means for feeding blanks successively to the die, and means for straightening the blanks during their passage to the die.
20. In a machine of the class described, the combination of a reciprocating ram, a die, a punch free of connection with said ram, means for delivering the power of the ram to the punch adjacent to the cutting part thereof from a point in the rear of such cutting part, means for indexing the die and
- the blank carried thereby, automatically operative means for positioning the die after each indexing thereof, means carried by the ram for locking the die, means for feeding blanks successively to the die, and means for straightening the blanks during their passage to the die.
21. In a machine of the class described, the combination of means for punching blanks from the center thereof outwardly, said means including a die and a punch, means for delivering power to the punch adjacent to the cutting part thereof from a point in the rear of such cutting part, and means for indexing the die and the blank carried thereby.
22. In a machine of the class described, the combination of a reciprocating ram, a die, a substantially horizontally located punch, means for delivering the power of the ram to the punch adjacent to the cutting part thereof from a point in the rear of such cutting part, and means for indexing the die and the blank carried thereby.
23. In a machine of the class described, the combination of a reciprocating ram, a rotatable die, a punch for punching blanks from the center thereof outwardly, means for delivering the power of the ram to the punch adjacent to the cutting part thereof from a point in the rear of such cutting part, and means for indexing the die and the blank carried thereby.
24. In a machine of the class described, the combination of a reciprocating ram, a substantially horizontally located punch, a rotatable die, and means for indexing the die and thereby the blank on the reciprocation of said ram.
25. In a machine of the class described, the combination of a reciprocating ram, a substantially horizontally located punch, a rotatable die, means for indexing the die and thereby the blank on the reciprocation of said ram, and means for delivering the power of the ram adjacent to the cutting end of the punch from a point rearwardly thereof.
26. In a machine of the class described, the combination of a reciprocating ram, a substantially horizontally located punch, a rotatable die, means for indexing the die and thereby the blank on the reciprocation of said ram, means for delivering the power of the ram adjacent to the cutting end of the punch from a point rearwardly thereof, and means for feeding blanks to the die.
27. In a machine of the class described, the combination of a reciprocating ram, a substantially horizontally located punch, a rotatable die, means for indexing the die and thereby the blank on the reciprocation of said ram, means for delivering the power of the ram adjacent to the cutting end of the punch from a point rearwardly thereof,

and means for semi-automatically feeding blanks to the die.

28. In a machine of the class described, the combination of a reciprocating ram, a substantially horizontally located punch, a rotatable die, means for indexing the die and thereby the blank on the reciprocation of said ram, means for delivering the power of the ram adjacent to the cutting end of the punch from a point rearwardly thereof, and means for feeding blanks to the die, said means including a slotted push rod.

29. In a machine of the class described, the combination of a reciprocating ram, a substantially horizontally located punch, a rotatable die, means for indexing the die and thereby the blank on the reciprocation of said ram, means for delivering the power of the ram adjacent to the cutting end of the punch from a point rearwardly thereof, means for feeding blanks to the die, said means including a slotted push rod, and a spring-controlled member for holding the blank during a partial forward movement 25 of the push rod.

30. In a machine of the class described, the combination of a reciprocating ram, a substantially horizontally located punch, a rotatable die, means for indexing the die and thereby the blank on the reciprocation of said ram, means for delivering the power of the ram adjacent to the cutting end of the punch from a point rearwardly thereof, means for feeding blanks to the die, said means including a slotted push rod, and a spring controlled member for separating the blank from the push rod after it has been punched.

31. In a machine of the class described, the combination of a reciprocating ram, a substantially horizontally located punch, a rotatable die, means for indexing the die and thereby the blank on the reciprocation of said ram, means for delivering the power of the ram adjacent to the cutting end of the punch from a point rearwardly thereof, means for feeding blanks to the die, said means including a slotted push rod, and a spring controlled member for holding the blank during a partial forward movement 50 of the push rod and for separating the blank from the push rod after it has been punched.

32. In a machine of the class described, the combination of a reciprocating ram, a substantially horizontally located punch, a rotatable die, means for indexing said die on the reciprocation of said ram, and means for positioning the blank relatively to the die.

33. In a machine of the class described, the combination of a reciprocating ram, a substantially horizontally located punch, a rotatable die, means for indexing said die on the reciprocation of said ram, means for positioning the blank relatively to the die,

and means for delivering the power of the ram adjacent to the cutting end of the punch from a point rearwardly thereof.

34. In a machine of the class described, the combination of a reciprocating ram, a substantially horizontally located punch, a rotatable die, means for indexing said die on the reciprocation of said ram, and means for positioning the blank relatively to the die, said means comprising a plurality of 75 spring-actuated jaws.

35. In a machine of the class described, the combination of a reciprocating ram, a substantially horizontally located punch, a rotatable die, means for indexing said die 80 on the reciprocation of said ram, means for positioning the blank relatively to the die, said means comprising a plurality of spring-actuated jaws, and means for delivering the power of the ram adjacent to the cutting end 85 of the punch from a point rearwardly thereof.

36. In a machine of the class described, the combination of a reciprocating ram, a substantially horizontally located punch, a rotatable die, means for indexing said die 90 on the reciprocation of said ram, means for positioning the blank relatively to the die, said means comprising a plurality of spring-actuated jaws, means for delivering the power of the ram adjacent to the cutting 95 end of the punch from a point rearwardly thereof, and means for locking the die subsequent to the indexing thereof.

37. In a machine of the class described, the combination of a reciprocating ram, a substantially horizontally located punch, a rotatable die, means for indexing said die on the reciprocation of said ram, means for positioning the blank relatively to the die, said means comprising a plurality of spring-actuated jaws, means for delivering the power of the ram adjacent to the cutting end of the punch from a point rearwardly thereof, and means for locking the die subsequent 100 to the indexing thereof, said means comprising a pair of locking devices one automatically actuated by the ram operating mechanism and the other carried by the ram, said locking devices coming into action in sequence.

38. In a machine of the class described, the combination of a reciprocating ram, a rotatable vertically supported die, means for indexing the die and thereby the blank on the reciprocation of said ram, and a punch operated by said ram.

39. In a machine of the class described, the combination of a reciprocating ram, a rotatable vertically supported die, means for indexing the die and thereby the blank on the reciprocation of said ram, a punch operated by said ram, and means for delivering the power of the ram to the punch adjacent to the cutting part thereof from a point in the rear of such cutting part.

40. In a machine of the class described, the combination of a reciprocating ram, a rotatable vertically supported die, means for indexing the die and thereby the blank on the reciprocation of said ram, a punch operated by said ram, and means for delivering the power of the ram to the punch adjacent to the cutting part thereof from a point in the rear of such cutting part, said means comprising an inclinedly located member between the ram and the punch.

41. In a machine of the class described, the combination of a reciprocating ram, a swinging nut-castellating punch in position to be actuated by said ram, a nut blank die co-operating with said punch and constructed to receive said punch at one side, and means for supporting said die at its opposite side.

42. In a machine of the class described, the combination of a reciprocating ram, a swinging punch in position to be actuated by said ram, a die co-operating with said punch, and means for indexing the die and thereby the blank on the reciprocation of said ram.

43. In a machine of the class described, the combination of a reciprocating ram, a substantially horizontally located swinging punch, a rotatable die, and means for indexing the die and thereby the blank on the reciprocation of said ram.

44. In a machine of the class described, the combination of a reciprocating ram, a substantially horizontally located swinging punch, a vertically supported rotatable die, and means for indexing the die and thereby the blank on the reciprocation of the ram.

45. In a machine of the class described, the combination of a reciprocating ram, a substantially horizontally located swinging punch, a vertically supported rotatable die, means for indexing the die and thereby the blank on the reciprocation of the ram, and means located between the ram and the punch for actuating the latter.

46. In a machine of the class described, the combination of a reciprocating ram, a substantially horizontally located swinging punch, a vertically supported rotatable die, means for indexing the die and thereby the blank on the reciprocation of the ram, and means located between the ram and the punch for actuating the latter, said means comprising an inclinedly located member whereby the power of the ram will be delivered to the punch adjacent to the cutting part thereof from a point in the rear of such cutting part.

47. In a machine of the class described, the combination of a reciprocating ram, a shiftable nut-castellating punch located to extend transversely of the direction of movement of the ram, a nut-blank die constructed to receive said punch at one side, means for supporting the die at its opposite side, and

means for shifting the punch from the die on the raising of the ram.

48. In a machine of the class described, the combination of a reciprocating ram, a shiftable nut castellating punch located to extend transversely of the direction of movement of the ram, a nut blank die, and means for shifting the punch from the die on the raising of the ram, said shifting means comprising a resiliently actuated member located below said punch.

49. In a machine of the class described, the combination of a reciprocating ram, a rotatable die, means for indexing the die and thereby the blank, a pivotally supported punch, and means in engagement with the punch for releasing it from the die on the raising of the ram.

50. In a machine of the class described, the combination of a reciprocating ram, a rotatable die, means for indexing it and thereby the blank, a pivotally supported punch, and means in engagement with the punch for releasing it from the die on the raising of the ram, said means comprising a spring actuated plunger.

51. In a machine of the class described, the combination of a reciprocating ram, a vertically supported rotatable die, means for indexing it and thereby the blank, a pivotally supported punch carrier carrying a punch, and spring controlled means in continuous engagement with the punch carrier for releasing the punch from the die on the raising of the ram.

52. In a machine of the class described, the combination of a reciprocating ram, a vertically supported rotatable die, means for indexing it and thereby the blank, a pivotally supported punch carrier carrying a punch, spring controlled means in continuous engagement with the punch carrier for releasing the punch from the die on the raising of the ram, and means carrier by the punch carrier between the ram and the punch for delivering the power of the ram adjacent to the cutting part of the punch.

53. In a machine of the class described, the combination of a reciprocating ram, a vertically supported rotatable die, means for indexing it and thereby the blank, a pivotally supported punch carrier carrying a punch, spring controlled means in continuous engagement with the punch carrier for releasing the punch from the die on the raising of the ram, and means carried by the punch carrier between the ram and the punch for delivering the power of the ram adjacent to the cutting part of the punch, said means comprising an inclinedly located loosely supported member.

54. In a machine of the class described, the combination of a reciprocating ram, a punch, a rotatable die supported for rotatable movement in a vertical plane, a die

carrier having a series of slots therein, and means connected with the ram for engaging each of said slots successively to index the carrier and the die and thereby the blank.

55. In a machine of the class described, the combination of a reciprocating ram, a punch, a rotatable die supported for rotatable movement in a vertical plane, a die carrier having a series of slots therein, and means connected with the ram for engaging each of said slots successively to index the carrier and the die and thereby the blank, said indexing means comprising a swinging lever having a slot-engaging projection.

56. In a machine of the class described, the combination of a reciprocating ram, a punch, a rotatable die, a die carrier having a series of slots therein, and means connected with the ram for engaging each of said slots successively to index the carrier and the die and thereby the blank, said indexing means comprising a swinging lever having a slot-engaging projection having straight and tapered sides.

57. In a machine of the class described, the combination of a reciprocating ram, a slotted die, a slotted vertically supported die carrier, the slots of the carrier corresponding in number with the slots of the die, and means connected with the ram and coöperating with the slots of the carrier for indexing the die.

58. In a machine of the class described, the combination of a reciprocating ram, a slotted die, a slotted vertically supported die carrier, the slots of the carrier corresponding in number with the slots of the die, means connected with the ram and coöperating with the slots of the carrier for indexing the die, and locking means coöperating with the slots of the carrier for locking the carrier after each indexing thereof.

59. In a machine of the class described, the combination of a reciprocating ram, a slotted die, a slotted vertically supported die carrier, the slots of the carrier corresponding in number with the slots of the die, means connected with the ram and coöperating with the slots of the carrier for indexing the die, and locking means coöperating with the slots of the carrier for locking the carrier after each indexing thereof, said locking means having connection with the ram.

60. In a machine of the class described, the combination of a reciprocating ram, a slotted die, a slotted vertically supported die carrier, the slots of the carrier corresponding in number with the slots of the die, means connected with the ram and coöperating with the slots of the carrier for indexing the die, means coöperating with the slots of the carrier for positioning the carrier after each indexing thereof, and means carried by the ram for successively

engaging the slots of the carrier on the drop of the ram for locking the carrier against movement.

61. In a machine of the class described, the combination of a reciprocating ram, a slotted die, a slotted vertically supported die carrier, the slots of the carrier corresponding in number with the slots of the die, means connected with the ram and coöperating with the slots of the carrier for indexing the die, means coöperating with the slots of the carrier for positioning the carrier after each indexing thereof, and means carried by the ram for successively engaging the slots of the carrier on the drop of the ram for locking the carrier against movement, said locking means comprising a shearable tooth.

62. In a machine of the class described, the combination of a reciprocating ram, a die having a plurality of slots, a die carrier having a similar number of slots, and means carried by the ram for locking the die carrier against movement on the drop of the ram.

63. In a machine of the class described, the combination of a reciprocating ram, a die having a plurality of slots, a die carrier having a similar number of slots, and means carried by the ram for locking the die carrier against movement on the drop of the ram, said means comprising a shearable tooth.

64. In a machine of the class described, the combination of a reciprocating ram, a die having a plurality of slots, a die carrier having a similar number of slots, means carried by the ram for locking the die carrier against movement on the drop of the ram, and means connected with the ram for positioning the die carrier.

65. In a machine of the class described, the combination of a reciprocating ram, a die having a plurality of slots, a die carrier having a similar number of slots, means carried by the ram for locking the die carrier against movement on the drop of the ram, and means connected with the ram for positioning the die carrier, both of said means coöperating with slots of the carrier.

66. In a machine of the class described, the combination of a reciprocating ram, a die having a plurality of slots, a die carrier having a similar number of slots, means successively coöperating with the slots of the die carrier for indexing the carrier, and means successively coöperating with the slots of the carrier for locking the carrier.

67. In a machine of the class described, the combination of a reciprocating ram, a die having a plurality of slots, a die carrier having a similar number of slots, means successively coöperating with the slots of the die carrier for indexing the carrier, and means successively coöperating with the slots of the die carrier for positioning the carrier.

slots of the carrier for locking the carrier, said locking means comprising independent devices.

68. In a machine of the class described, the combination of a reciprocating ram, a die having a plurality of slots, a die carrier having a similar number of slots, means successively coöperating with the slots of the die carrier for indexing the carrier, and means successively coöperating with the slots of the carrier for locking the carrier, said locking means comprising independent devices both operative on the movement of the ram.

69. In a machine of the class described, the combination of a reciprocating ram, a die having a plurality of slots, a die carrier having a similar number of slots, means successively coöperating with the slots of the die carrier for indexing the carrier, and means successively coöperating with the slots of the carrier for locking the carrier, said locking means comprising independent devices both operative on the movement of the ram, one carried by the ram and the other connected therewith.

70. In a machine of the class described, the combination of a reciprocating ram, a die having a plurality of slots, a vertically supported die carrier having a similar number of slots, means operative on the movement of the ram and coöperating with the successive slots of the die carrier for indexing the carrier, and means operative on the movement of the ram and coöperating with successive slots for locking the carrier.

71. In a machine of the class described, the combination of a reciprocating ram, a die having a plurality of slots, a vertically supported die carrier having a similar number of slots, means operative on the movement of the ram and coöperating with the successive slots of the die carrier for indexing the carrier, and means operative on the movement of the ram and coöperating with successive slots for locking the carrier, said locking means comprising independent devices.

72. In a machine of the class described, the combination of a reciprocating ram, a die having a plurality of slots, a vertically supported die carrier having a similar number of slots, means operative on the movement of the ram and coöperating with the successive slots of the die carrier for indexing the carrier, and means operative on the movement of the ram and coöperating with successive slots for locking the carrier, said locking means comprising independent devices one carried by the ram and the other connected with the ram.

73. In a machine of the class described, the combination of a reciprocating ram, a die having a plurality of slots, a vertically supported die carrier having a similar number of slots, means operative on the movement of the ram and coöperating with the successive slots of the die carrier for indexing the carrier, and means operative on the movement of the ram and coöperating with successive slots for locking the carrier, said locking means comprising independent devices one carried by the ram and the other connected with the ram.

74. In a machine of the class described, the combination of a die having a plurality of slots, a vertically supported die carrier having a similar number of slots, means coöperating with the slots of the carrier for indexing the carrier, and means operative on the movement of the ram and coöperating with successive slots for locking the carrier, said locking means comprising independent devices one carried by the ram and the other connected with the ram and engaging adjacent slots after each indexing of the carrier.

75. In a machine of the class described, the combination of a die having a plurality of slots, a vertically supported die carrier having a similar number of slots, means coöperating with the slots of the carrier for indexing the carrier, its die and the blank, means coöperating with the slots of the carrier for locking the carrier, a reciprocating ram, and a pivotally supported punch.

76. In a machine of the class described, the combination of a die having a plurality of slots, a vertically supported die carrier having a similar number of slots, means coöperating with the slots of the carrier for indexing the carrier, its die and the blank, means coöperating with the slots of the carrier for locking the carrier, a reciprocating ram, a pivotally supported punch, and means between the ram and the punch for transmitting the power to the ram adjacent to the cutting end of the punch.

77. In a machine of the class described, the combination of a die having a plurality of slots, a vertically supported die carrier having a similar number of slots, means coöperating with the slots of the carrier for indexing the carrier, its die and the blank, means coöperating with the slots of the carrier for locking the carrier, a reciprocating ram, a pivotally supported punch, means between the ram and the punch for transmitting the power of the ram adjacent to the cutting end of the punch, and means for releasing the punch from the die on the raising of the ram.

78. In a machine of the class described, the combination of a die having a plurality of slots, a vertically supported die carrier having a similar number of slots, means coöperating with the slots of the carrier for indexing the carrier, its die and the blank, means coöperating with the slots of the carrier for locking the carrier, a reciprocating ram, a pivotally supported punch, means between the ram and the punch for transmitting the power of the ram adjacent to the cutting end of the punch, means for releasing the punch from the die on the raising of the ram, and means for feeding blanks to the die.

79. In a machine of the class described, the combination of a die having a plurality of slots, a vertically supported die carrier having a similar number of slots, means coöperating with the slots of the carrier for indexing the carrier, its die and the blank, means coöperating with the slots of the carrier for locking the carrier, a reciprocating ram, a pivotally supported punch, means between the ram and the punch for transmitting the power of the ram adjacent to the cutting end of the punch, means for releasing the punch from the die on the raising of the ram, and means for feeding blanks to the die.

operating with the slots of the carrier for indexing the carrier its die and the blank, means co-operating with the slots of the carrier for locking the carrier, a reciprocating ram, a pivotally supported punch, means between the ram and the punch for transmitting the power of the ram adjacent to the cutting end of the punch, means for releasing the punch from the die on the raising of the ram, and means for feeding blanks to the die and comprising a magazine and manually operated means.

79. In a machine of the class described, the combination of a die having a plurality of slots, a vertically supported die carrier having a similar number of slots, means co-operating with the slots of the carrier for indexing the carrier its die and the blank, means co-operating with the slots of the carrier for locking the carrier, a reciprocating ram, a pivotally supported punch, means between the ram and the punch for transmitting the power of the ram adjacent to the cutting end of the punch, means for releasing the punch from the die on the raising of the ram, and means for feeding blanks to the die and comprising a magazine and manually operated means including a reciprocating plunger.

80. In a machine of the class described, the combination of a die having a plurality of slots, a vertically supported die carrier having a similar number of slots, means co-operating with the slots of the carrier for indexing the carrier its die and the blank, means co-operating with the slots of the carrier for locking the carrier, a reciprocating ram, a pivotally supported punch, means between the ram and the punch for transmitting the power of the ram adjacent to the cutting end of the punch, means for releasing the punch from the die on the raising of the ram, means for feeding blanks to the die and comprising a magazine and manually operated means including a reciprocating plunger, and means for positioning the blank carried by the plunger.

81. In a machine of the class described, the combination of a reciprocating ram, a nut-blank die, means for supporting it at one side, a nut-castellating punch, said die constructed to receive said punch at its opposite side, and nut-blank feeding means comprising a reciprocating plunger, effective to axially support said blank in the die during the castellating thereof.

82. In a machine of the class described, the combination of a reciprocating ram, a nut-blank die, means for supporting it at one side, a nut-castellating punch, said die constructed to receive said punch at its opposite side, nut-blank feeding means comprising a reciprocating plunger adapted to enter the die and a magazine, and means

for retarding the blank during the feeding movement thereby to permit the plunger to fully enter the blank and feed it into the die.

83. In a machine of the class described, the combination of a reciprocating ram, a nut-blank die, means for supporting it at one side, a nut-castellating punch, said die constructed to receive said punch at its opposite side, and nut-blank feeding means comprising a reciprocating plunger adapted to enter the die, a magazine, means for reciprocating said plunger, and means for removing the blank from the plunger during the withdrawal of said plunger from the die.

84. In a machine of the class described, the combination of a reciprocating ram, a nut-blank receiving die, means at one side of said die for supporting it, and a nut-castellating punch extending transversely of the direction of movement of the ram and having a cutting end adapted to project into said die at its opposite side.

85. In a machine of the class described, the combination of a reciprocating ram, a die and a punch, blank feeding means comprising a reciprocating plunger and a magazine, manually operated means for reciprocating said plunger, said plunger having a slotted end, and means for positioning the blanks as they are pushed into the die by the plunger.

86. In a machine of the class described, the combination of a reciprocating ram, a die and a punch, blank feeding means comprising a reciprocating plunger and a magazine, manually operated means for reciprocating said plunger, said plunger having a slotted end, and means for positioning the blanks as they are pushed into the die by the plunger, said positioning means having a plurality of shiftable jaws.

87. In a machine of the class described, the combination of a reciprocating ram, a die and a punch, blank feeding means comprising a reciprocating plunger, and means between the die and the punch for preventing the slugs from the blanks passing into the die.

88. In a machine of the class described, the combination of a reciprocating ram, a die and a punch, blank feeding means comprising a reciprocating plunger, and means between the die and the punch for preventing the slugs from the blanks passing into the die, said means comprising a plate having an opening for the end of the punch.

89. In a machine of the class described, the combination of a reciprocating ram, a vertically supported and rotatable die, a pivotally supported substantially horizontally located punch, a reciprocating blank feeder, and means between the die and the punch for preventing the slugs from the blanks from being carried into the die.

90. In a machine of the class described, the combination of a reciprocating ram, a vertically supported and rotatable die, a pivotally supported substantially horizontally located punch, a reciprocating blank feeder, and means for swinging the punch after each punching operation. 65
91. In a machine of the class described, the combination of a reciprocating ram, a vertically supported and rotatable die, a pivotally supported substantially horizontally located punch, a reciprocating blank feeder, and means for freeing the blank from the feeder at the end of the punching operations. 10
92. In a machine of the class described, the combination of a reciprocating ram, a nut blank die, a nut castellating punch having a rib-formed cutting surface having parallel side walls, and means for holding the punch against endwise play. 15
93. In a machine of the class described, the combination of a reciprocating ram, a substantially horizontally supported pivoted punch carrier, a nut-castellating punch therein having a rib-formed cutting surface having parallel side walls, and means for holding the punch against endwise play. 20
94. In a machine of the class described, the combination of a reciprocating ram, a cone-shaped nut-blank receiving die, means at one side for supporting said die, a nut-castellating punch extending transversely of the direction of movement of the ram and having a cutting end adapted to project into said die at its opposite side. 25
95. In a machine of the class described, the combination of a reciprocating ram, a substantially horizontally supported pivoted punch carrier, a punch therein, and adjustable means for holding the punch against endwise play and including a cylindrical lock located in cylindrical ways of the carrier. 30
96. In a machine of the class described, the combination of a reciprocating ram, a substantially horizontally supported pivoted punch carrier, a punch therein, adjustable means for holding the punch against endwise play and including a cylindrical lock located in cylindrical ways of the carrier, and means carried by the carrier and located between the punch and the ram for transmitting power from the ram adjacent to the cutting end of the punch. 35
97. In a machine of the class described, the combination of a reciprocating ram, a substantially horizontally supported pivoted punch carrier, a punch therein, adjustable means for holding the punch against endwise play and including a cylindrical lock located in cylindrical ways of the carrier, means carried by the carrier and located between the punch and the ram for transmitting power from the ram adjacent to the cutting end of the punch. 40
98. In a machine of the class described, the combination of a reciprocating ram, a pivotally supported punch carrier adapted to carry a punch, and means connected only with the punch carrier and extending rearwardly from the front end of said carrier for transmitting power from the ram adjacent to the cutting part of the punch. 45
99. In a machine of the class described, the combination of a reciprocating ram, a pivotally supported punch carrier adapted to carry a punch, and means extending rearwardly from the front end of said carrier for transmitting power from the ram adjacent to the cutting part of the punch, said means including a loosely supported and sliding ram extension. 50
100. A punch holder adapted to carry a punch, and means carried by the holder and extending rearwardly from the front end thereof and terminating adjacent to the top side of the holder for transmitting power adjacent to the cutting part of the punch. 55
101. A punch holder adapted to carry a punch, adjustable means in the rear of the punch for locking the punch against endwise play, and means for pivotally supporting the punch. 60
102. A punch holder adapted to carry a punch, adjustable means in the rear of the punch for locking the punch against endwise play, said means comprising a cylindrical lock located in cylindrical ways of the holder, and means for pivotally supporting the punch. 65
103. A punch holder adapted to carry a punch, adjustable means in the rear of the punch for locking the punch against endwise play, means for pivotally supporting the punch, and means carried by the holder and extending rearwardly from the front end thereof for transmitting power adjacent to the cutting end of the punch. 70
104. A punch holder adapted to carry a punch, adjustable means in the rear of the punch for locking the punch against endwise play, said means comprising a cylindrical lock located in cylindrical ways of the holder, means for pivotally supporting the punch, and means carried by the holder and extending rearwardly from the front end thereof for transmitting power adjacent to the cutting end of the punch. 75
105. A pivotally supported punch holder adapted to carry a punch, adjustable means carried by said holder for locking the punch against endwise play, and means carried by the holder for transmitting power adjacent to the cutting end of the punch from a point in the rear thereof. 80

106. In a machine of the class described, the combination of a ram, a pivotally supported swinging punch holder free of connection with said ram and extending transversely to the direction of movement of said ram, a nut-castellating punch carried by said holder, a die constructed to receive the cutting end of said punch at one side, and means at the opposite side of said die for supporting it for rotary movement.
107. In a machine of the class described, the combination of a reciprocating ram, a pivotally supported swinging punch holder adapted to carry a punch free of connection with said ram, and means for transmitting power from one part of the holder to that part of the punch located at another part of said holder.
108. In a machine of the class described, the combination of a reciprocating ram, a pivotally supported swinging punch holder adapted to carry a punch free of connection with said ram, means for transmitting power from one part of the holder to that part of the punch located at another part of said holder, and means including a cylindrical member carried by the holder for preventing endwise play of the punch.
109. In a nut castellating machine, the combination of a rotatable die, an oscillating punch working at approximately right angles to the die axis, means for indexing the die and thereby the blank, and means for operating the punch.
110. In a nut castellating machine, the combination of a rotatable die, an oscillating punch working at approximately right angles to the die axis, means for indexing the die and thereby the blank, means for operating the punch, and means for locking the die.
111. In a machine of the class described, the combination of nut blank means, a punch supported to castellate the blank only from the center thereof outwardly at each stroke of the punch, and means for imparting relative motion to said blank and punch.
112. In a machine of the class described, the combination of nut blank holding means, a punch supported to castellate the blank only from the center thereof outwardly at each stroke of the punch, and means for imparting relative motion in a vertical plane to said blank and punch.
113. In a machine of the class described, the combination of a nut blank die, means for supporting said die, a single punch supported to castellate the blank only from the center thereof outwardly at each stroke of the punch, and power-driven means for imparting relative motion to said die and punch.
114. In a machine of the class described, the combination of a nut blank holding means, a punch supported to castellate the blank only from the center thereof outwardly at each stroke of the punch, and means for imparting motion to said punch.
115. In a machine of the class described, the combination of die, means for supporting it, a punch supported to castellate the blank only from the center thereof outwardly at each stroke of the punch, and means for imparting motion to said punch.
116. In a machine of the class described, the combination of a nut blank die, means for supporting it with its axis in a horizontal plane, a punch supported to castellate the blank only from the center thereof outwardly at each stroke of the punch, and means for imparting motion to said punch in a vertical direction.

Signed at Cleveland, in the county of Cuyahoga and State of Ohio, this 15th day of July, 1914.

OSCAR A. SMITH.

BENJAMIN F. RINDFLEISCH.

Copies of this patent may be obtained for five cents each, by addressing the "Commissioner of Patents, Washington, D. C."

It is hereby certified that in Letters Patent No. 1,157,258, granted October 19, 1915, upon the application of Oscar A. Smith and Benjamin F. Rindfleisch, of Cleveland, Ohio, for an improvement in "Machines for Castellating Nuts," errors appear in the printed specification requiring correction as follows: Page 9, line 109, after claim 52, for the word "carrier" read *carried*; page 14, line 43, claim 111, after the word "blank" insert the word *holding*; and that the said Letters Patent should be read with these corrections therein that the same may conform to the record of the case in the Patent Office.

Signed and sealed this 13th day of January, A. D., 1920.

[SEAL.]

M. H. COULSTON,
Acting Commissioner of Patents.

Cl. 0—72.
